UNITED STATES PATENT OFFICE

HARRY LEBERMAN, OF NEW YORK, N. Y., ASSIGNOR TO GROOVE LOCK CO. INC., OF NEW YORK, N. Y., A CORPORATION OF NEW YORK

FASTENING DEVICE FOR BAGS

Application filed May 14, 1930. Serial No. 452,356.

The present invention relates to hand and other types of bags, and has more particular reference to an improved fastening means applied to bag frames.

5 An object of the present invention is to provide a fastening means for bag frames of the type wherein a pair of opposed members are pivotally connected together and are adapted to be swung toward and from each other in the act of closing and opening the bag, and wherein the fastening means will not readily spring open and wherein it cannot be easily or accidentally moved into open position.

10 Another object of the present invention is to provide a fastening means of this character which lends itself readily to ornamentation, which may be quickly and easily manipulated into locking and released positions, which serves to maintain the opposed members of the frame in true alignment with one another and which effectively holds the frames in closed position throughout their lengths when the lock is closed.

15 Another feature of the present invention is to provide a fastening device for bag frames which does not extend beyond the top of the frame and which admits of the use of frames of channel construction so that the frames with the fastening device thereon may be applied to bags of various types and of various materials without modification in the general frame structure.

20 With the foregoing and other objects in view, the invention will be more fully described hereinafter, and will be more particularly pointed out in the claims appended hereto.

25 In the drawing, wherein like symbols refer to like or corresponding parts throughout the several views.

30 Figure 1 is a perspective view of a bag frame in closed position and showing a fastening device constructed according to the present invention applied thereto.

35 Figure 2 is a similar view with the fastening device released and the members of the frame in open position.

40 Figure 3 is a fragmentary upper edge view 50 of the bag frame in locked position and with

the top wall of the bag frame broken away.

Figure 4 is a similar view with the fastening or locking device in open or released position, and

45 Figure 5 is a transverse section taken through the locked frames substantially on the line 5—5 of Figure 3.

55 Referring to the drawing, the bag frame including the locking feature comprises a pair of frame members 10 and 11. Each frame member comprises a U-shaped body portion, the same being constructed of channel shape with the channel opening inwardly adapted to receive the edge of the bag material at the top of the bag in the usual manner.

60 The opposed arms of the members 10 and 11 at each end of the bag are pivotally connected together by hinges 12, the hinges being secured to the free ends of the arms of the members 10 and 11 and arranged so that the members 10 and 11 when swung together at their upper ends lie in face to face contact as shown clearly in Figures 1, 3, 4 and 5.

65 One of the frame members, such as 10, is provided along its upper edge with a top channel rail 13 which is of a width equal substantially to twice the thickness of the frame 10, or equal to the thickness of both the frames 10 and 11 when in closed position.

70 This top rail 13 overhangs the member 11 when in closed position and at its outer flange is secured to the outer edge portion of the member 10, as shown clearly in Figure 5.

75 The inner flange of the rail 13, at an intermediate point, is interrupted or cut away to provide a recess 14 and the recess is so positioned that substantially one-half the length thereof is located centrally between the ends of the frame while the other portion or half of the recess is offset toward one end of the frame.

80 The centrally disposed portion of the recess 14 is provided with a depending locking lip 15 which, as shown in Figures 2 and 5, extends downwardly from the top portion of the channel rail 13 and is of less width than the inner flange of the channel rail 13 so as to project into the recess 14 but a slight distance at the top thereof.

85 The opposite frame member 11 is provided, in register with the recess 14, with a guide 90

95 100

member 16 in the form of a T-head which may be of the length of the recess 14 so as to pass therethrough with a snug fit to insure the proper registration of the frame members 10 and 11 during the opening and closing of the frame members, and the guide member 16 is provided at its outer edge and opposite ends with rounded corners 17 adapted to engage against the flange of the rail 13 at opposite ends of the recess 14 to insure the free and easy opening of the frame. Also the guide member 16 is integral with and projects from the opposing side wall of frame 11 so as to be in axial alignment with the longitudinal axis of the channel rail 13.

15 A locking slide 18 is mounted upon the guide member 16 and, as shown in Figure 5, is of channel form with the free edges thereof turned inwardly beneath the head of the guide member 16 so as to hold the slide 18 thereto and admit of the shifting of the slide 18 lengthwise of the guide member 16.

The slide 18 is of less length than that of the guide member 16 and is proportioned to freely enter the offset portion of the recess 14 when the slide member 18 is shifted in one direction to register with said portion of the recess. The slide member 18 is adapted to be shifted lengthwise of the guide 16 so as to bring the slide member 18 behind the locking lip 15, as shown in Figures 3 and 5, and the slide member 18 is of sufficient height or thickness above the guide member 16 as to engage against the rear or inner side of the lip 15 for holding the frame members together.

For the purpose of shifting the slide 18, the finger hold 19 is provided upon the outer face of the frame member 11 and this finger hold 19 may be of any suitable configuration but preferably is in the form of an elongated flat body piece adapted to lie flat against the frame members 10 and 11 when closed, as shown in Figure 5, and is preferably of a width not greater than the combined widths of the upper portions of the frame members. This finger hold 19 may be of any suitable construction and may be in the form of a hollow shell adapted to support and carry a surface ornamentation 20 which may comprise stones, a composition material or the like. The finger member 19 is connected to the locking slide 18 by a relatively narrow shank or neck portion 21 which extends inwardly from the inner side of the member 19 and is connected to the slide 18 at a point below the upper face thereof so as to accommodate the locking lip 15 when the slide is adjusted into position behind the same.

In the use and application of the bag frame the frame members 10 and 11 are secured in the usual manner to the upper free edge portions of a bag of cloth, leather, metal or any other material or combinations thereof and the members 10 and 11 swing upon their

pivots or hinges 12 in the usual manner of opening and closing the bag. When the bag is to be closed the members 10 and 11 are moved at their outer ends toward each other with the locking slide 18 shifted into position to register with the enlarged portion of the recess 14. As the frame members 10 and 11 approach a closed position the guide 16 enters the recess 14 and insures the proper registering of the members 10 and 11 as the opposite ends of the guide 16 abut the ends of the recess 14. The guide 16 and the locking slide 18 therefore enter the recess, as soon as the frame members 10 and 11 are brought together in face to face relation, the finger hold 19 is forced endwise of the frame member 11 so as to shift the locking slide 18 toward the other end of the guide 14 and back of the depending locking lip 15. The frictional contact between the slide 18 and its guide 16 and the finger hold 19 and the adjacent outer side face of the frame member 11 yieldingly hold the parts in interlocking relation and prevent the accidental unlocking or releasing of the frame members 10 and 11 incident to the handling of the bag or the contact of the finger hold 19 with surrounding objects.

For the purpose of suspending the bag frame the member 10 may be provided at its opposite outer corners with loop portions 22 for the reception of the end links of a chain, the ends of a strap or the like.

It is obvious that various changes and modifications may be made in the details of construction and design of the above specifically described embodiment of this invention without departing from the spirit thereof, such changes and modifications being restricted only by the scope of the following claims.

What is claimed is:

1. A fastening device for a pair of movable pivotally connected inverted U-shaped bag frames, the first of which has a channel rail on its top side adapted to overlap the top of the second frame when in closed relation, and have the sides thereof in alignment with the outer sides of the frames, said rail having a longitudinally recessed side portion intermediate the ends thereof with a depending locking lip disposed in the recess and facing the inner side of the other opposing frame, a guide strip projecting from the inner face of the other frame, having a length substantially equal to that of the recess and adapted to fit into the recessed portion of the rail on the first frame so as to be in axial alignment therewith, a locking member slidably mounted on said guide strip for fitting into the recess to slide behind the depending lip when moved in one direction, and a vertically disposed finger hold connected to said slide arranged against the outer side face of the opposing frame where-

by to push one frame against the other in closed position and slide the locking member into the recess and against the inside of the depending lip, said finger hold having its top portion co-extensive with the top of the channel rail and one face in flush sliding contact with the outer face of the second frame.

2. In a hand bag having a pair of hinged inverted U-shaped frames, a fastening device comprising an inverted channel rail with one side wall integrally extending from the outer face of one of the frames and adapted to overlap the top of the other frame when in closed relation, said rail having a longitudinal recess in its inner side face, and a locking lip depending into said recess and extending throughout a portion of the length thereof, a guide strip projecting from the inner abutting side wall of the opposing frame for holding the opposite sides of the frames in closed relation and passing the free edge of the locking lip in the recess, a locking slide on the guide strip for passing a portion of said recess between the locking lip and one end of the recess, and an elongated finger hold integrally connected with the locking slide, having one side making a flush sliding contact with the outer side face of the second frame and with the inner side face of the rail upon closing the frame, said finger hold being adapted for moving the locking slide against the inner face of the locking lip to retain the frames in abutting face to face relation.

35 In testimony that I claim the foregoing as my invention, I have signed my name hereto.

HARRY LEBERMAN.
